SPINDLE MOUNTING

Dimitri G. Soussloff, Warwick, and Arnold C. White, Greenwood, R. I., assignors to Universal Winding Company, Cranston, R. I., a corporation of Massachusetts

Application April 25, 1951, Serial No. 222,837

14 Claims. (Cl. 57—89)

1

This invention relates to a spindle mounting for a twisting machine, and, more particularly, relates to a spindle mounting of the kind in which the spindle is rotatably supported on a pivotally mounted arm.

The manufacture of textile material frequently involves the preliminary step of twisting the strand material, such as textile yarn, from which the textile material is to be formed, in order to obtain a desired mechanical characteristic or appearance in the textile material. Such preliminary twisting of strand materials is done on a twisting machine, and one type of machine commonly employed for this purpose is known in the art as an "uptwister".

The present invention may be used advantageously on the "uptwister" type of twisting machine, and in order to facilitate an understanding of the invention an embodiment of the invention which may be used in this type of winding machine is illustrated and described herein.

A conventional "uptwister" consists of a plurality of yarn twisting and winding pairs, each such pair comprising a rotatable spindle adapted to support a yarn supply, and a yarn take-up device which includes a bobbin, spool or other core onto which the twisted yarn is wound.

It is well understood in the art that in machines of this kind the spindle carrying the yarn supply is rotated at high speed as the yarn is drawn off the yarn supply by the take-up device. The degree of twist imparted to the yarn is determined by the relation between the winding speed of take-up device and the speed at which the yarn supply is rotated by the spindle.

It is a common practice in the art to drive the spindles in a machine of this kind by means of an endless belt which drivingly engages the whorls of a series of spindles arranged side-by-side along the length of the machine. Such driving means provides a simple and inexpensive construction which is capable of delivering equal driving power to each individual spindle, thus assuring a constant spindle speed throughout the machine, and a uniformly twisted product from all of the winding pairs. In order to obtain a constant spindle speed throughout the machine it is necessary to maintain all the spindles in contact with the belt constantly by mounting the spindle so that the spindle may follow the undulations of the driving belt which occur at high belt speeds. This is generally accomplished by mounting the spindle on a swing arm pivoted to a stand which is supported on the frame of the machine. The pivoted swing arm is spring-pressed in the direction of the driving belt, and thus establishes a yielding driving engagement between the spindle and the driving belt.

Continuous and trouble-free operation of machines of this kind can be obtained only when the forces by which the spindles are held in con-

2

stant driving engagement with the belt are sufficient to insure uniform spindle speed, and at the same time not so excessive as to cause undue wear of the belt and the spindle supporting bearings in the spindle mounting. Operation of the machine causes sustained vibrations in the spindle mounting. Occasional adjustments of the spring tension by which the driving engagement is maintained are therefore necessary. Spindle mountings heretofore employed have been difficult to adjust.

One of the purposes of this invention is to provide a spindle mounting of the kind discussed above in which the tension of the spring that acts to hold the spindle in engagement with the driving belt may be adjusted quickly and conveniently without dismantling any part of the spindle mounting or the machine with which it is associated.

In order that the spindle may quickly follow the undulations of the driving belt it is necessary that the pivoted swing arm be free to move easily about its pivot. As the yarn supply carried on the spindle, the spindle itself, and the spindle step represent a considerable amount of weight disposed on the distal end of the swing arm, the swing arm tends to bind on its pivotal support and thus slows the response of the spindle to undulations of the driving belt.

A further object of this invention is to provide a novel means for pivoting the swing arm which provides a sturdy bearing between the pivot post and its supporting means, and which utilizes the pivot means to house the adjustable spring arrangement by which the spindle and the driving belt are held in driving engagement. This construction provides a compact, efficient and readily adjustable spindle mounting.

A further object of this invention is to provide a spindle swing having novel means for lubricating the bearings between the pivot post and its support.

A further object of this invention is to provide a spindle swing having means whereby the bearings between the pivot post and its support can be provided with sufficient lubrication to last an extended period of time.

It is desirable in a winding machine of the kind described above to have means for interrupting the drive of each individual spindle, so that the machine operator may, as necessary, stop the spindle and replace an empty yarn supply with a full one. Such replacement by the operator is facilitated by providing means on the spindle mounting which act to arrest the rotation of the spindle immediately following its disengagement from the driving belt, and by providing further means which prevent the spindle from being dislodged from the spindle mounting when the operator thereafter doffs the empty yarn supply.

A further object of this invention is to provide

an improved means for withdrawing the spindle from engagement with the driving belt of the machine which acts to lock the spindle in its disengaged position subject to quick, easy release.

A further object of this invention is to provide an improved means for preventing the spindle from being dislodged from the spindle mounting when an exhausted yarn supply is removed from the spindle.

Further objects and advantages of the invention will be apparent from the following description of the invention and from the accompanying drawings.

In the drawings:

Figure 1 is a top plan view of a spindle mounting constructed according to this invention;

Fig. 2 is a front elevation view of the same spindle mounting showing also the lower portion of the whorl of a spindle mounted thereon;

Fig. 3 is a vertical sectional view on line 3—3 of Fig. 1;

Fig. 4 is a side elevational view of the same mounting showing its operative relationship to a frame member, shown in dotted lines, and a driving belt, shown in dotted lines, with which the mounting may be associated;

Fig. 5 is a section on the line 5—5 of Figure 1 showing the cam means by which the spindle mounted on the spindle mounting may be retracted from engagement with a driving belt in the position in which it effects such disengagement; and

Fig. 6 is a vertical sectional view on line 5—5 of Figure 1 showing the same cam in the position which it assumes when the spindle carried by the mounting is in engagement with a driving belt.

In general, the embodiment of the invention illustrated in the drawings comprises a base member or stand 10 on which a swing arm 12 is pivotally supported. The distal end of the swing arm is adapted to carry a spindle support indicated generally at 14. A spindle comprising a spindle blade 15, to which is fixed the spindle whorl 16, is rotatably supported on the support in the conventional manner. This spindle carrying portion of the arm is pressed in a direction about its pivot which will cause the spindle carried by the support to move into engagement with a spindle driving means, such as the driving belt 17 shown in the dotted lines in Figure 4. The swing arm is urged in this direction by an adjustable resilient means which includes the helical spring 18 shown in Figure 3. The spindle carried on the support may be disengaged from the driving belt by operation of a hand lever 20 which rocks a cam 22 against a camming surface provided on the swing arm. The positions of the cam 22 relative to the camming surface on the swing arm when the spindle is disengaged from, or engaged with, the driving belt are shown, respectively, in Figures 5 and 6. Means are provided to prevent the cam 22 from being rocked beyond its dead center of relationship with the camming surface on the arm 12 so that the swing arm may be locked in the position wherein the spindle is disengaged from the driving belt subject to quick release by a light upward pressure on the lever 20.

The illustrated spindle mounting also comprises a brake member 24 and a spindle retaining means 26 which are supported on an upright post 28. This post is supported on the stand 10 and extends upwardly therefrom through an arcuate aperture 30 in the swing arm 12. The brake member 24 is positioned so that it engages the whorl 16 of the spindle carried by the support 14

when the spindle is swung from engagement with the driving belt 17 by means of the lever 20. The spindle retaining means 26 is positioned so that a terminal portion thereof overlies a flange provided on the spindle whorl 16 when the swing arm is rocked into its spindle disengaging position, shown in Figure 5, thereby preventing the spindle from being dislodged from the mounting when a yarn package or core supported on the spindle is doffed.

In the particular embodiment of the invention generally described above, the base member or stand 10 is a generally rectangular-shaped block having a flat rear surface 34 which may suitably engage a longitudinally extending frame member of the machine with which the spindle mounting is to be associated, such as the member 36 shown in dotted lines in Figure 4, and to which member it may be fixed by studs such as 38 and 40, also shown in dotted lines in Figure 4.

The swing arm 12 is pivotally supported on the stand 10 by means including the tubular pivot post 42 which is fixedly secured within an aperture provided toward one end of the swing arm. The upper end of the tubular pivot post 42 terminates in the plane of the upper surface of the swing arm, and the lower portion thereof extends downwardly from the underside of the swing arm into the recess 44 provided in the stand 10. As shown in Figure 3, the recess 44 may be provided by forming a through-going, vertically disposed passage in the stand 10 which is closed off at its lower end by means of a plug 46 having an upstanding circular flange 48. Within this circular flange the lower end 50 of the tubular pivot post 42 may be journaled. Toward the upper end of the recess 44 the wall thereof is cut back to receive the annular bearing 52 composed of a porous bearing material. The diameter of the bore of bearing 52 is less than the diameter of recess 44 to provide a space between pivot post 42 and the wall of recess 44 adapted to contain a supply of lubricant. The bearing 52 closely encircles the tubular post 42. The wall of the cut back portion of the recess 44 is also recessed to receive the annular oil wick 54 which is thus positioned to contact and lubricate the bearing 52. Wick 54 is provided with a tail-like depending portion 55 which is received in longitudinal groove 53 in stand 10 to have its lowermost end adjacent the lower bearing 48, 50, and in contact with lubricant contained in the space between pivot post 42 and the wall of recess 44. It will thus be seen that the lower bearing formed by circular flange 48 and the lower end 50 of pivot post 42 is immersed in a supply of lubricant, and that the upper bearing is lubricated by lubricant passing up the tail-like portion 55 of wick 54 and through porous bearing member 52.

It will be observed that the bearing 52 engages the pivot post 42 along a substantial portion of its length. This construction, whereby the lower end of the post is steadied within the circular flange 48 and a large area of the intermediate portion turns within the bearing 52, insures that the swing arm 12 will not bind on its pivot even though the relatively large weight of the spindle mounting and the yarn package carried thereby is disposed on the distal end of the swing arm.

The distal end of the swing arm 12 is provided with an aperture which is circular in cross section, and which receives the shell 56 of the spindle support 14. The spindle support comprises a spindle step 58 in which the spindle blade 15 is journaled for rotation, the spindle blade hav-

ing fixed thereto the whorl 16, as previously mentioned. The spindle step is elastically supported on the shell 56 by means which include the rubber rings 62, 64 which are bonded to the shell and to the metal washers 66, 68. The metal washers 66, 68 along with the sleeve 70 supportably engage the spindle step. The spindle mounting is secured to the swing arm by the set screw 72 which threadedly engages the walls of an aperture in the end of the swing arm and abuts the portion of the shell 56 which covers the inner opening of this aperture.

As previously stated, the spindle carrying portion of the swing arm is spring pressed about its pivot in the direction which will cause the spindle whorl 16 to engage the driving belt 17. The adjustable resilient means by which this is accomplished includes the helical spring 18 which at its lower end is fixedly positioned with respect to the stand 10 by means of the pin 80. This pin threadedly engages the walls of a horizontally disposed aperture in the lower portion of the stand 10 and extends through a circumferentially extending aperture in the tubular member 42, as may be seen best in Figure 3. The end of the pin 80 is provided with two circumferentially extending grooves, and the lower end of the spring 18 is formed to pass downwardly in one of these grooves on one side of the pin, and to pass beneath the pin and have its terminal portion rest in the other groove on the other side of the pin. This arrangement firmly anchors the lower end of the spring against rotative movement with respect to the stand 10 and also locks pivot post 42 against removal from stand 10 while permitting it to pivot freely therein. The other end of the spring is fixed to a plug-like anchorage 86 which is positioned within the upper end of the tubular member 42 so that it may be freely rotated therein. It will be seen that the tension on the spring 18 may thus be adjusted by rotating the anchorage 86. To facilitate such adjustments a tool receiving recess 88 is provided on the top surface of the anchorage. The spring means, thus adjusted to the desired degree of tension, is secured to the swing arm 12 by means of the set screw 90 which threadedly engages the walls of an aperture formed in the end of the swing arm and which extend through a registering aperture in the tubular member 42 to abut the spring anchorage 86 set in the desired position. With the anchorage 86 thus locked to the swing arm, the spring 18 acts to swing the arm about its pivot and move the spindle carrying portion of the arm towards the driving belt, whereupon a driving engagement is established between the belt and the spindle whorl. It will be seen that in addition to obtaining a compact and efficient construction wherein the spring means is housed within the pivot for the swing arm, the construction is also such that the tension on the spring may be quickly and readily adjusted. Manipulation of the set screw 90 and the anchorage 86 only are necessary to adjust the tension on the spring. Both the anchorage 86 and the set screw 90 are positioned where they are readily accessible and can be easily manipulated at the same time. It will be apparent that adjustment is accomplished by first loosening the set screw 90 and thereafter turning the anchorage 86 until the desired tension has been established on the spring. The set screw may then be tightened to complete the adjustment.

It has been previously mentioned that the spindle mounting comprises means including the

cam 22 for swinging the spindle carrying portion of the arm 12 away from the driving belt 17 against the action of the spring 18, and for locking the arm 12, subject to quick release, in the position wherein the spindle is disengaged from the driving belt. The upper rear corner of the side of the stand 10 shown in Figures 5 and 6 is cut back to provide a two-sided well having sides 94, 96 and a bottom ledge 92 which underlies the cam 22. One end of the lever 20 (shown in dotted lines in Figure 1) is angled-over and journaled in a horizontally disposed passage in the upper rear portion of the stand 10. This passage at one end opens onto the wall 96, and the cam 22 is fixed to the portion of the lever 20 which extends from this end of the passage. The cam 22 may thus be rocked in a vertical plane between the positions in which it is shown in Figures 5 and 6, respectively, by imparting an upward or downward movement, as may be required, to the handle 98 which is fixed to the free end of the lever 20, and which is conveniently disposed across the front of the stand 10.

The cam 22 is provided with a nose portion 100 which works against the camming surface 102 provided on the arm 12 to swing the arm against the action of the spring 18 to the position wherein the spindle carried by the arm is disengaged from the driving belt. The camming surface 102 is formed in part on one surface of a lug 104 which extends from the underside of the arm 12 into the two-sided well previously mentioned.

The relationship of the cam 22 and the camming surface 102 when the swing arm 12 is at the limit of its pivotal movement towards the driving belt is shown in Figure 6. A spring 106, shown in Figure 4, which is coiled about the lever 20 and fixed to the lever and to the stand 10, tends to move the lever 20 and the cam 22 toward the positions in which they are illustrated in Figure 6. This upward rocking movement of the cam nose 100 is limited by the flush engagement of a surface 108 on the cam with the surface of the pad 110 which is formed on the ledge 92. At this limit of upward movement the cam nose is free from the camming surface 102 and whorl 16 is in engagement with belt 17 in response to the action of the spring 18.

The spindle carried by the arm 12 may be disengaged from the driving belt by moving the handle 98 downwardly from the position illustrated in Figure 6 to that shown in Figure 5, thus causing the cam nose 100 to move downwardly along the camming surface 102 and to swing the arm 12 against the action of the spring 18 to the position illustrated in Figure 5. This downward rocking movement of the cam nose is limited by the flush engagement of the planer surface 112 on the cam with the surface of the pad 110. The surface 112 is positioned on the cam so that the downward rocking movement of the cam is stopped when the cam assumes, or passes slightly beyond, its dead center relationship with the camming surface 102. At this point, the force applied to the cam by the spring pressed arm 12 has no vector about the pivot point of the cam and together with the action of brake 24, to be explained in detail hereinafter, establishes a frictional drag on the nose of the cam which is sufficient to overcome the tendency of the spring 106 to raise the cam to the position illustrated in Figure 6. A slight upward movement of the cam nose imparted by a slight upward movement of the handle 98, moves the cam off its dead center and both the spring 106 and

the spring 18 then acts to return the cam and the swing arm to the positions illustrated in Figure 6, wherein the spindle carried by the arms engages the driving belt.

The spindle brake 24, previously mentioned, is supported on the post 28 and consists of a resilient metal strip having its intermediate portion curved concentrically with the outside diameter of the spindle whorl 18. To this intermediate portion is fixed a composition friction pad 116, seen best in Figure 1, against which the spindle whorl is brought to bear when it is withdrawn from engagement with the driving belt in the manner described above to flex the resilient metal strip and thus apply a braking effect to the spindle. The braking effect thus obtained may be regulated, and adjustments to compensate for wear of the friction pad may be made by rotatably repositioning the post 28 within the recess in the stand 10 within which it is supported. The post is retained in a position thus selected by means of the set screw 113 which threadedly engages a horizontally disposed aperture in the stand and which at the end of the aperture opening into the recess abuts the lower end of the post. In addition to applying a braking effect to the spindle the flexed resilient metal strip also exerts a force on swing arm 12, through whorl 18 and spindle blade 15, towards its belt engaging position. This force exerted by brake 24 in addition to the force exerted in the same direction by spring 18 is sufficient to overcome the tendency of spring 106 to pivot cam 22 to its unlatched position illustrated in Fig. 6.

The spindle retaining means 26 consists of a horizontally disposed plate which is also fixed to the post 28 to overlie the swing arm 12. The plate extends radially from the post to the point where the edge of the plate overlies a flange 20 formed on the bottom edge of the spindle whorl 18 when the swing arm is locked in the position wherein the spindle carried by the arm is disengaged from the driving belt. The plate 26 thus positioned prevents the spindle from being dislodged from its mounting when a yarn package, or a core thereof, is removed from the spindle blade.

The claims of invention that are desired to be secured by Letters Patent are set forth below:

1. A spindle mounting for a twisting machine comprising a base member, a swing element adapted to receive means for rotatably supporting a spindle and having an aperture therein, a tubular member extending from said swing element and secured thereto in said aperture, a recess provided in said base member to receive the said extending tubular member, whereby said swing element is pivotally supported on said base member, a helical spring disposed within the said tubular member, means supported on the base member fixedly positioning one end of said spring with respect thereto, a spring anchorage adjustably supported in said tubular member for adjusting the tension of said spring, the other end of said spring being fixed to the said anchorage, and means for releasably securing said swing element to said anchorage in a desired position of adjustment of the anchorage.

2. A spindle mounting for a twisting machine comprising a base member, a horizontally disposed swing element adapted to receive means for rotatably supporting a spindle, said swing element being provided with an aperture toward one end thereof to receive said spindle support

means and a second aperture towards its other end to receive a tubular member, a downwardly extending tubular member fixed within said second aperture and terminating at its upper end in the plane of the upper horizontal surface of said swing element, said base member being provided with a recess to receive said downwardly extending portion of said tubular member, whereby the said swing element is supported for pivotal movement on said base member, adjustable spring means acting on said swing element and tending to impart pivotal movement in one direction to said swing element, said spring means comprising a helical spring disposed within said tubular member, means supported on said base member fixedly positioning one end of the spring with respect thereto, a plug-like spring anchorage rotatably supported in the upper end of said tubular member, the other end of the spring being fixed to said anchorage, whereby the tension of said spring may be adjusted by rotating the said anchorage, and means for releasably securing said swing element to said anchorage when the desired degree of tension has been imparted to said spring by the rotation of said anchorage to a selected position.

3. A spindle mounting for a twisting machine comprising a base member, a swing element pivotally carried by said base member adapted to rotatably support a spindle, spring means urging said swing element in a direction which will cause the spindle to be drivingly engaged by an associated driving means, means for releasably withdrawing the spindle from driving engagement with said driving means comprising a cam mounted on said base member and adapted to be rocked from a first position to a second position, a camming surface positioned on said swing element to cooperate with said cam, means for rocking said cam from said first position to said second position whereby it engages said surface to move said swing element away from said spindle driving means against the action of said spring, and a resilient braking member adapted to be engaged by a portion of said spindle as it is moved away from said spindle driving means to stop the rotation of said spindle, said resilient braking member exerting a force on said swing element to prevent said cam from rocking from said second position to said first position until said rocking means is actuated.

4. In a spindle mounting for a twisting machine of the kind in which a swing element carrying a rotatably supported spindle is pivotally supported on a base member and spring urged in a direction which will cause the spindle to be drivingly engaged by an associated driving means, means for releasably withdrawing the spindle from driving engagement with said driving means comprising a cam rockably mounted on said base member, a camming surface positioned on said swing element to cooperate with said cam, a hand lever fixed to said cam for rocking said cam into operative engagement with said surface whereby the spindle supporting portion of said swing element is moved away from said spindle driving means against the action of the said spring, and means for preventing the said cam from being rocked toward said camming surface beyond its dead center relationship thereto, whereby the spindle bearing portion of said swing element may be locked away from the spindle driving means subject to quick release.

5. In a spindle mounting for a twisting ma-

chine of the kind claimed in claim 4 in which said swing element is horizontally disposed and has a depending lug and in which said camming surface is formed partially on one side of said lug, the said base member being arranged and constructed to cooperate with said lug to limit the pivotal movement of said swing element away from the spindle driving means.

6. In a spindle mounting for a twisting machine of the kind in which a spindle is rotatably supported on a swing element which is pivotally mounted on a base member and spring urged towards a spindle driving means, and which further includes means operable to withdraw the spindle from engagement with the spindle driving means by causing the spindle carrying portion of the swing element to pivot away from the spindle driving means; a spindle having a flange on the whorl thereof, a spindle brake supported on the base member and positioned to be engaged by the spindle when the spindle is swung from engagement with the spindle driving means, and a retaining element supported on said base member and positioned to closely overlie the said flange when the spindle is moved into engagement with said brake, whereby a package supported on the spindle may be removed therefrom without dislodging the spindle from its mounting.

7. In a spindle mounting for a twisting machine, a stationary brake element, means for receiving a spindle having a flange portion provided thereon, means for moving the spindle from engagement with a spindle driving means into engagement with said brake element, and a retaining means positioned to closely overlie said flange portion of said spindle when said spindle is in its brake engaging position, whereby a package may be removed from the spindle in its last said position by an upward pull without dislodging the spindle from its mounting.

8. A spindle mounting for a twisting machine comprising a base member, a swing element pivotally supported on said base member and adapted to receive means for rotatably supporting a spindle, a resilient member fixed at one point to said base member and adjustably fixed to said swing element, whereby the spindle carrying portion of said swing element is yieldingly urged in one direction towards a spindle driving means, means for releasably moving the spindle carrying portion of said swing element in the other direction comprising a cam rockably mounted on said base member, a camming surface positioned on said swing element to cooperate with said cam, a hand lever fixed to said cam for rocking said cam into operative engagement with said camming surface, whereby the spindle carrying portion of said swing element is moved in said other direction against the action of said resilient member, and means preventing said cam from being rocked towards said camming surface beyond its dead center relationship thereto, whereby the spindle carrying portion of said swing member may be locked at the limit of its movement in the said other direction subject to quick release and movement in said one direction in response to the action of said resilient member.

9. A spindle mounting for a twisting machine as claimed in claim 8 which also comprises means for receiving a spindle having a flange portion provided thereon, and a retaining means supported on said base member and positioned to closely overlie said flange portion of said spindle when the spindle carrying portion of said swing element approaches the limit of its movement in the said other direction.

10. A spindle mounting for a twisting machine as claimed in claim 9 which also comprises a stationary brake element, said brake element being positioned to be engaged by said spindle as the said spindle carrying portion of said swing element approaches the limit of its movement in the said other direction.

11. A spindle mounting for a twisting machine as claimed in claim 10 which comprises a post extending upwardly from said base member through an arcuate aperture in said swing element, said brake element and said retaining means being fixed to said post to extend radially therefrom above said swing element, and said post being adjustably secured to said base element, whereby the said brake and retaining means may be positioned as described with respect to the limit of movement of said spindle bearing portion of said swing member in the said other direction.

12. A spindle mounting for a twisting machine comprising a base member, a swing element adapted to receive means for rotatably supporting a spindle, a tubular member extending from said swing element and secured to said swing element, a recess in said base member, bearings fixed in said recess to receive the said extending tubular member, said bearings engaging said tubular member over a substantial portion of its length, a helical spring disposed within said tubular member, means supported on the base member fixedly positioning one end of said spring with respect thereto, a spring anchorage adjustably supported in said tubular member for adjusting the tension of said spring, the other end of said spring being fixed to said anchorage, and means for releasably securing said swing element to said anchorage in a desired position of adjustment of the anchorage.

13. A spindle mounting for a twisting machine comprising a base member, a swing element pivotally carried by said base member and adapted to receive means for rotatably supporting a spindle, a pivot post extending from said swing element and secured thereto, a recess in said base member, upper and lower bearing elements in said recess rotatably supporting said pivot post, and means for supplying said upper bearing element with lubricant from adjacent said lower bearing element.

14. A spindle mounting for a twisting machine comprising a base member, a swing element pivotally carried by said base member and adapted to receive means for rotatably supporting a spindle, a pivot post extending from said swing element and secured thereto, a recess having a cross-sectional area greater than the diameter of said pivot post in said base member, upper and lower bearing elements in said recess rotatably supporting said pivot post in said base member and providing a reservoir for lubricant between said post and the wall of said recess, and means for transporting lubricant from said reservoir to said upper bearing element.
